UNITED STATES PATENT OFFICE.

DAVID NETTENSTROM, OF CHICAGO, ILLINOIS.

FOLDING TENT.

1,219,847.

Specification of Letters Patent. Patented Mar. 20, 1917.

Application filed August 31, 1911. Serial No. 646,979.

To all whom it may concern:

Be it known that I, DAVID NETTENSTROM, a citizen of the United States, residing at Chicago, in the county of Cook and State of Illinois, have invented new and useful Improvements in Folding Tents, of which the following is a specification, reference being had to the accompanying drawings, forming a part thereof.

10 The purpose of this invention is to provide in combination, a tent frame and covering therefor adapted to be readily folded into a small parcel for ease of transportation or convenience of storage. It consists 15 of the features and elements described and shown in the drawings as indicated in the claims.

In the drawings:—

Figure 1 is a medial section of a tent having the frame embodying this invention.

Fig. 2 is a somewhat diagrammatic view of the frame in folded position.

Fig. 3 is a detail plan view of one member of the pivot block, 2.

25 Fig. 4 is a section taken as indicated at line 4—4 on Fig. 3.

Fig. 5 is a detail plan view of the cover plate of the pivot block, 2.

Fig. 6 is a medial section of a tent having 30 the end framing constructed similar to that shown in Fig. 1, such framing being connected by a special form of folding ridge pole truss.

Fig. 7 is a transverse section taken as indicated at line 7—7 on Fig. 6.

Fig. 8 is a diagrammatic view indicating the arrangement in folded position of the frame in Fig. 6.

Fig. 9 is a detail plan view of the locking 40 means of the folding member of the ridge pole truss.

Fig. 10 is a detail section taken as indicated at line 10—10 on Fig. 9.

This invention is applicable to any form 45 of tent in which a vertical pole or post is ordinarily employed for supporting the peak or ridge pole of the tent, the frame shown in the drawings being intended as a substitute for such vertical supporting pole, and having two advantages over the latter, namely, that it leaves the entire floor space 50 clear of poles and that it can be folded into a shorter parcel than a single unitary pole.

As illustrated in Figs. 1 to 5, the frame is applied to a tent made in the form of a regular hexagon with a pyramidal roof, but it may be understood that the particular features of the construction are equally applicable to many other forms of tents, including both those which are formed regularly about 60 a vertical axis, as is the first form illustrated and those employing a ridge pole, such as for example, the familiar "wall tent."

The frame comprises a central vertical rod, 1, carrying fittings, 2, 3 and 4, to which 65 are connected the members of a plurality of trusses, corresponding in number to the several faces of the tent roof, and each carrying at its extremity a supporting pole, 5. Each truss consists of a rafter, 6, pivoted at 70 one end in the block, 2, a strut, 7, pivotally connecting the block, 3, with a point somewhere near the middle of the rafter, 6, and a tension member or stretcher 8, pivoted between the block, 4, and the end of the 75 rafter, 6.

The construction of the central fittings 2, 3 and 4 is indicated in Fig. 3, which shows the preferred form as consisting of a circular disk axially apertured at, *a*, to admit the 80 rod, 1, and formed with a series of radial recesses, *b*, each dimensioned to receive the end of one of the truss members indicated in Fig. 3 as the rafters, 6. Between each pair of recesses, *b*, the disk has formed on one 85 face a pair of lugs, *c*, *c*, which serve to position a hoop of heavy wire, *d*, upon which the several truss members, 6, are pivoted. A cover plate, *e*, which is shown in Fig. 4, provided with corresponding downwardly extending lugs, *f*, dimensioned to fit between the lugs, *c*, *c*, for holding the hoop, *d*, in place, is clamped in position by a pair of retaining bolts, *g*, *g*, and completes the fitting. The fitting, 2, is rigidly secured to the upper 95 end of the rod, 1, by a nut, *1^a*, screwed down upon the reduced end of the rod, but the fittings 3 and 4, are slidable along the rod, being only retained against escaping from it by means of a terminal flange, *1^b*, at the 100 lower end.

The bracket, 9, at the lower end of each rafter, 6, in addition to securing the end of the member, 8, is provided with a hinge, *9^a*, by which the post, 5, is connected to the 105 rafter, 6. Now, when it is desired to take

down the tent and fold up the frame for transporting or storing it, the canvas covering, 10, having been first removed, and rolled or folded in any desired manner, the posts, 5, 5 may each be swung about their hinges, 9^a, to positions parallel to their respective rafters, 6; then if the central fittings, 3 and 4, be pushed along the rod, 1, toward the fitting, 2, all the frame members will assume positions parallel to the rod, 1, as indicated in Fig. 2. It will be understood, that in passing through the horizontal position each of the struts, 7, will tend to bow outwardly its corresponding rafter, 6, but that as the 10 block, 3, rises above this position the rafter, 6, will be allowed to resume its normal form, and the frame can be easily folded up. For opening out the frame, the reverse of the above operation will be employed, and when 15 the central fitting, 3, has reached its lowest position, as shown in Fig. 1, the resistance of the rafters, 6, to bending will operate to retain the fitting, 3, in this position and hold the frame open.

20 In combination with the above described frame there is shown in Fig. 6, a folding truss which may be substituted for a ridge pole in any form of tent in which such a member would ordinarily be employed. This 25 truss as shown, consists of two panels connected end to end to a vertical strut rod, 11, which may carry triangular frames similar to those shown in Fig. 1, grouped around the rod, 1, such frames extending to either side 30 of the ridge pole and terminating in supporting posts, 5, as indicated in Fig. 7. Each panel of the ridge pole truss consists of a ridge pole, 12, which is a compression member, and tension cord, 13, and two flexible diagonal ties, 14.

40 Figs. 9 and 10 indicate the construction of the member, 12, which comprises two parts, 12^a and 12^b, pivotally connected side by side, the part, 12^a, extending beyond the pivot 45 point for some distance, and a ferrule, 15, slidably carried on the member, 12^b, being adapted to prevent buckling of the element, 12, when in use, by being positioned to embrace also the extending end of the member, 50 12^a. For closing up the ridge pole panel it is then only necessary to slip the ferrule, 15, off from the end of the part, 12^a, so as to permit the member, 12, to be folded downwardly, as shown in Fig. 8; the strut, 11, 55 will then approach the rod, 1, and may be disposed parallel to it, while the cords, 13 and 14, will be easily accommodated in the spaces between the various parts of the structure when folded. Both panels of the truss 60 being closed, the end portions of the frame may be brought together to form a comparatively compact package, whose length will be that of the rafters, 6, as may be noted by reference to Fig. 8.

I claim:—

65

1. A folding tent frame comprising a central fitting and rafters pivotally connected thereto extending outwardly and downwardly therefrom, a second central fitting and stretchers pivotally connected thereto at one end extending outwardly therefrom and having their opposite ends hinged to the respective rafters, a third central fitting positioned above the second and struts pivotally connected thereto at one end extending outwardly and upwardly therefrom and having their opposite ends hinged to the respective rafters, whereby said third fitting opposes movement of the second fitting toward the first, the length of each strut between pivot centers being less than the distance between its hinged connection with the rafter and the pivotal connection of such rafter with the first fitting, so that said frame may be collapsed by folding the struts and stretchers 80 upwardly toward said first central fitting.

70

2. A folding tent frame comprising a central fitting and rafters pivotally connected thereto extending outwardly and downwardly therefrom, a second central fitting and stretchers pivotally connected thereto at one end extending outwardly and downwardly therefrom and having their opposite ends hinged to the respective rafters, means limiting the unfolding of said stretchers at such 90 downwardly inclined position, and struts hinged to the respective rafters converging downwardly and arranged to react against the second fitting for opposing the collapse 95 of the frame.

100

3. A folding tent frame comprising two central fittings vertically separated when the frame is open, a stop which determines the limit of such separation and disengageable locking means for holding the parts at such 105 limit, together with rafters and stretchers pivotally connected to the upper and lower central fittings respectively and all extending outwardly and downwardly therefrom, the outer end of each stretcher being hinged to one of the rafters at a plane considerably below the lower central fitting and its associated stop and locking means when said fitting is at the limit indicated.

110

4. A tent frame comprising a folding truss 115 panel having a pair of vertical strut rods, a pivotally jointed member pivotally connecting the upper ends of said rods; means on the jointed member adapted to prevent the closing of its joint; a tension member connecting the lower ends of the rods; diagonal ties joining the opposite corners of the quadrilateral thus formed; a series of rafters, pivotally connected to the upper end of each of said rods; a block slidably mounted upon 120 each rod; a series of struts each pivotally connected at one end to the block and at the other end to a point on one of the rafters; a

125

stop on the lower end of the rod adapted to limit the sliding movement of the block, the angle between the rod and the strut being acute when the block is at such limit and a tension member extending from the lower portion of the rod to a second point on each rafter.

In testimony whereof I have hereunto set my hand at Chicago, Ill. this 24th day of August, 1911.

DAVID NETTENSTROM.
